UNITED STATES PATENT OFFICE.

CARL G. WERNMARK, OF WALLA WALLA, WASHINGTON, ASSIGNOR OF ONE-HALF TO
WILL N. ESTES, OF WALLA WALLA, WASHINGTON.

AUTOMATIC BLOCK-TURNING MACHINE.

Application filed August 15, 1927. Serial No. 212,898.

This invention relates to automatic block turning machines, more particularly a machine adapted to turn wooden heels as used in the shoe industry.

5 One of the objects of this invention is to provide an automatic machine that will form turned heels in pairs from a given pattern form whereby the pairs of heels are identical in form and weight.

10 Another object of the invention is to provide an automatic machine that may constitute a multiplicity of heel turning units all governed by a single pattern form.

15 A further object of the invention is to provide an automatic machine that is adapted to use various forms of patterns by the proper adjustment of the parts.

20 With these and other objects in view reference is now made to the accompanying drawings in which

Fig. 1 is a plan view of the block turning machine as designed to turn four blocks simultaneously;

25 Fig. 2 is a side elevation taken on the line 2—2 of Fig. 1, showing the chute and its operating mechanism;

Fig. 3 is a sectional elevation taken on the line 3—3 of Fig. 1, showing the spur center rotating mechanism and shifting means;

30 Fig. 4 is a front elevation of a fragment of the machine;

Fig. 5 is an enlarged view of one of the centering mechanisms;

35 Fig. 6 is a sectional elevation of one of the centers showing its sliding arrangement;

Fig. 7 is an end elevation of a plate adapted to fit into and adjust the chute to accommodate other forms of blocks shown in relation to the chute (dotted);

40 Fig. 8 is a perspective view thereof;

Fig. 9 is a transverse view of that part of Fig. 2 showing the chute in its retracted position; and

Fig. 10 is a perspective view of the yoke.

45 Having reference to the drawings like numerals refer to like parts throughout the several views and the numeral 1 refers to a frame consisting of the usual uprights 2 and cross-pieces 3.

50 Rotatably mounted in the cross-pieces of

the frame is a laterally positioned carriage rail 4 extending throughout the lateral length of the frame and mounted on this rail is a reciprocating tool carriage 5 that, in addition to sliding back and forth thereon, is 55 adapted to rock in a vertical plane for a purpose to be explained.

A counter-balance 6 is mounted on the carriage and is positioned with respect to the fulcrum, i. e. the carriage rail 4, to balance 60 the forwardly extending parts consisting of the main table 7 and forwardly extending arms 8 in which are suitably journaled a tool shaft 9 to be hereinafter described.

65 A main shaft 10 is rotatably mounted in and extends laterally of the frame and may be driven in any suitable manner, as by a prime mover not shown, and a cross-shaft 11 connects the main shaft with the carriage rail 4, for the rotation of that member, preferably by means of upright shafts 12 suitably journaled in and supported by the frame. 70

As these shafts 10, 11, and 12, operate the reciprocating means of said carriage, and as the reciprocating movement of said carriage 75 is relatively slow, worms 13 and worm-gears 14 are mounted respectively on these shafts in engageable relation and are used to reduce the speed of the reciprocating mechanism which will now be described.

80 The reciprocating mechanism consists of a screwthreaded shaft 15 formed as part of the carriage rail 4 with its threads running in two directions, and alternately engaging this screwthreaded shaft are internally threaded 85 segments 16 securely mounted in yokes 17 for movement therewith to alternately engage or disengage the respective threads on said rail, and slidably secured in the yoke are bearings or sleeves 18 having a common center, both of 90 which bearings are adjustably and securely mounted on a guide-shaft 19 secured to the carriage by hangers 18^a as shown, or in any suitable manner with said yokes being adapted to alternately slide backward or forward 95 on the bearings to threadedly engage the segments with said screwthreaded shaft 15.

To move the yokes 17 at a predetermined time and in synchronized relation to the other parts of the machine, to be explained, 100

a tripping rail 20 is provided having a segmental track 21 common to the respective yokes, with yielding members 22 attached to the side of the rail 20, at opposite ends of 5 said track to alternately engage the yokes as they approach either end of the track to suddenly move the yoke when it comes to the end of the track thereby causing the yoke to engage or disengage the screwthreaded 10 shaft 15 through the medium of the threaded segments and thus provide for alternate right or left, or reciprocating movement of said carriage.

Obviously the tripping rail must remain 15 stationary with respect to the reciprocating movement of the carriage and for this purpose the tripping rail is secured to the rail 4 by an arm 21^a, and a collar 21^b adapted to prevent its tendency to longitudinal movement. 20

The yoke is provided with a roller 22^a secured thereto and positioned to register alternately with the respective sides of the track as the yoke is moved backward or forward by the yielding members 22, the roller and the track thus serving to lock the respective segments both into or out of engagement with the threads of the screwthreaded shaft. 30

Mounted on the tool shaft 9 are cutting tools 23, one tool for each block (to be hereinafter explained), and these tools consist preferably of wheels having their perimeters formed to constitute a multiplicity of cutting edges. Shifting collars 24 are also adjustably mounted on said shaft 9, for a purpose to be explained. 35

In a turning operation it is a recognized fact that either the article to be turned must 40 rotate with a high rate of speed or, as where a drilling operation takes place, the tool must operate at a relatively high rate of speed. In this case the tools are rotated at a relatively high speed and independently 45 of other parts of the machine by the preferred means of a motor 25 mounted on and traveling with said carriage and suitably connected with said tool shaft by a belt 26 or equivalent means. 50

Mounted on the carriage 5, preferably 55 loosely upon the tool shaft 9 thereof, is a pilot wheel 27 preferably of equal diameter with the cutting tools, and its face 28 is rounded to conform with the cutting edges of the tools and the pilot wheel is positioned in alignment with said cutting tools, for a purpose to be explained. 60

A bed rail 29 extends laterally of and is secured to the frame 1 in any suitable manner, 60 and a bed plate 30, also extended laterally and paralleling the rail, is situated centrally of the frame, and the bed rail and bed plate form a bed on which one or more relatively 65 low speed centering mechanisms 31 are slidably supported for lateral adjustment. 65

The number of these mechanisms is only limited by the length of the carriage, this in turn limiting the length of the tool shaft, and this the number of centering mechanisms supported by said bed. 70

The mechanisms 31 consist of a table 32 mounted on and supported by the bed rail and bed plate respectively in which table is mounted spur centers 33 the centers being adapted to rotate by means of a square or 75 spline shaft 34 on which the centers are slidably mounted, and being adapted to slide in opposed directions by shifting levers 35 consisting of a main lever 36 pivotally attached to the top of the mechanisms, as at 80 36^a, and extended rearwardly to terminate in an elongated sleeve 37 curved to form an arc, the radius of which extends from the center of the carriage rail 4, and the main lever 36 is extended forward for engagement 85 with a hand operated, laterally positioned, rod 38 wherewith the shifting of the centers may be done manually. A secondary lever 39 is also pivotally attached to the table at the rear end thereof and is extended forward and terminates in a cross-arm 40 which joins the two levers for united action, whereby an advancing or retracting movement of the opposed centers is accomplished simultaneously. Where the levers are automatically operated the collars 24 on the tool shaft 9 are set to properly engage the sleeve 37 of the main lever 36 when the carriage is in one position while the shoulder 41 of the tool will engage the sleeve when the carriage 100 5 is in the opposite position. By this means it is obvious that as the carriage performs its reciprocating movement it automatically advances and retracts the centers to engage or disengage the blocks 42 to be turned. 105

This movement of the shifting means 35 also acts to start or stop the rotation of the centers as follows; the driving means for said centers consists of a worm 43 mounted on and operable by means of the main shaft 10, and a worm gear 44 mounted on a drive shaft 45 extended rearwardly, with this shaft carrying a worm 45^a engageable with a worm wheel 46 mounted on the square shaft 34, with a clutch 47 inserted in said drive shaft. 110

Now, to stop the rotation of the centers, it is necessary to disengage the clutch and for this purpose a bell crank 48 is provided which is pivoted to the table 32 with one arm 48^a of the crank engaging the driving clutch 47 to 120 slidably operate that member, and with the other arm 48^b extended forward to pivotally engage the main shifting lever, as at 48^c, whereby as said shifting lever is moved by the reciprocating movement of the carriage 125 the clutch will become disengaged as the centers are retracted and released from the block, and their rotation will then cease. Obviously, the reverse movement will serve to start the rotation of said centers. 130

Obviously with the centering mechanism resting on the bed the said spur centers are in line, and to control and guide the movement of the tools a form-holding spur center 5 49 is suitably mounted on said bed in any approved manner and in aligned and rotatable relation with the spur centers of the centering mechanisms, with a wood center 50 suitably aligned and mounted for manual operation 10 in the usual manner of such centers to secure a pattern form 51.

The pattern form may be of any shape within the limits of this machine, but in this case it consists of a form of the nature of a pair of heels joined together at their inner-faces, with the form positioned to frictionally engage, and rotate the pilot wheel 27, in a manner that the pilot wheel which is loosely mounted on the tool shaft 9 will follow precisely 20 the contour of said pattern form, whereby the cutting tools will be guided in their operation.

For this purpose the centering mechanism 31 operates at a relatively low speed and by 25 this means the pattern rotates slowly and raises and lowers the pilot wheel with a slow movement, as the carriage, and with it the cutting tools, are reciprocating back and forth, and, at the same time, the blocks 42 are 30 rotated in synchronized relation with the form.

As the blocks and the form 51 have a relatively long major axis and a relatively short minor axis it is obviously essential that the 35 major axis of the block and form have the same position and the same angle of inclination initially.

For this purpose a feeding chute 52 is provided that is pivotally mounted on the upright 54, which in turn is supported by said bed rail 29, for slidable adjustment thereon, with the chute positioned initially with its discharge end 53 interposed between the spur centers of the adjacent mechanisms, and with 45 its form adapted to coincide with the contour of the blocks.

This initial position of the chute provides for the true disposition and inclination of the block as the centers are advanced for the purpose of gripping said block, and arms 53^a are provided rigidly attached to and movable with one of said chutes and extended to engage said pattern form, as the chute assumes its initial position (the pattern form coming 50 to rest at the moment that the chute assumes this position), with the arms engaging the long side of the pattern form, thereby causing the pattern form to assume the identical angle of inclination with the block at the initial 55 moment of being seized by said centers.

Let it be here understood that while the chute has been described as positioned between the spur centers of adjacent mechanisms it is obvious that the two outside chutes 60 65 will be adjacent to the centering mechanism

on one side only and that while spur centers are expressed throughout, a wood center will obviously be used at the right side of the right-hand block.

The feeding chute 52 is pivotally mounted 70 on an upright 54 supported by the bed rail 29 as above mentioned and is adapted to retire its discharge end as the centers seize the block in a manner to be explained, and a curved arm 55 is provided, preferably attached to the upright 54 in a position that its upper end will pass through an orifice 56 in the bottom 57 of said chute as the chute is retired. By so doing this curved arm engages the first of succeeding blocks and as the chute is retired it 80 presses these blocks backward to provide for the free movement of the block (secured in the centers) during the turning operation.

The chute 52 is retired by means of clutch controlled cams 58 positioned in operable contiguity with the respective chutes, the cam shaft 59 being driven by a cross-shaft 60 from the main shaft 10, by any suitable gearing, as 60^a and 60^b, and mounting a clutch 61 which is automatically released and engaged in the 90 following manner; the clutch is mounted on the cam-shaft, and a bell crank 62 is pivotally attached to the table 32 of the mechanism, and has one end in operable association with the cam clutch while the other end is operably 95 associated with the aforementioned driving clutch 47.

From the above it is obvious that as the shifting levers 35 (including levers 36 and 39) are shifted to release the lowermost of 100 the blocks 42 the bell crank will operate to disconnect the driving clutch 47 and as a result the rotation of the centers will cease, and as this driving clutch moves for disengagement it actuates the cam clutch 61, through the 105 bell crank 62, which becomes engaged to retire the chute by moving the cam in a manner to permit the discharge end of the chute to lower by gravity.

It is also obvious that as the cam completes 110 its revolution, the chute will be restored to its initial position, then with the movement of the carriage synchronized to operable relation with the driving mechanism, the spur centers will be caused to seize the blocks and start 115 their rotation, and the chute will then again retire, the cam clutch remaining disengaged until the completion of the turning operation, when the operation will be repeated.

A stop 63 is provided at the lower end of the 120 chute against which the blocks rest in their initial position preparatory to turning, and, while other chutes may be substituted to receive blocks of a different cross-section it is advisable that an adjusting plate 64 having 125 its own stop 63^a be provided to rest in the bottom of said chute, as a substitute therefor, to change the lateral inclination thereof to accommodate the different blocks.

From the above it now becomes obvious 130

that the blocks should first be sawed from a stick to assume a general outline of the frustum of a cone and with the major and minor axes equal to or slightly in excess 5 of the similar axes of the pattern block.

Now, with a prime mover such as a motor or gas engine, (not shown) attached to the main shaft 10 by means of the pulleys 65 (which may include a clutch if desired) the 10 main driving shaft 10 is rotated and the worm wheel 14 mounted thereon rotates one of the vertical shafts 12 through its worm 13 which in turn rotates the cross shaft 11, and this shaft communicates the motion and power to 15 a separate vertical shaft 12 and that shaft in turn rotates the carriage rail 4 by means of the worm-wheel 14 associated with the rail 4 for the purpose.

While worms and worm-wheels are herein 20 specified it is for the purpose of showing only that the mechanism associated with the turning of the block is to be provided with a slow motion and hence, other means may be used if desired. This reduction of speed is done 25 primarily to give relatively slow motion to the pattern block so that the movement imparted to the pilot wheel thereby will be uniform and accurate.

On the other hand the carriage also has a 30 slow (reciprocating) movement, and by means of an independent motor mounted thereon and suitably connected to the tool shaft a high speed may be obtained and imparted to the cutting tools whereby those tools 35 may function properly to work the blocks to a form corresponding to the pattern form during the course of operation.

The blocks now being sawed to the proper 40 shape they are slidably inserted into the chute, the chute now having an inclined position for the purpose of bringing the block to the initial position, preparatory to turning, by gravity.

By referring to Fig. 1 it will be noted that 45 the pattern forms have a projecting surface in excess of the width of the block and this surface provides a support for the pilot wheel to maintain the cutting tools in a position free of contacting any metal parts when these cutting tools have reached the maximum reciprocating movement. By this means the cutting tools may operate on the blocks either from right to left or left to right, as desired 50 by the operator, although it will probably be found advantageous to start the turning operation on the apex of the block and move thence to the base.

With the blocks now inserted and with the 60 cutting tools in position shown in Fig. 1 it will now be assumed that the hopper is retiring. As the hopper retires the arms 53^a release the pattern form at the moment the spur 65 centers seize the block and at this moment the driving clutch is engaged and the blocks and

the pattern forms begin their uniform rotation.

From this moment the carriage will proceed to the right and the cutting tools will engage the blocks in conformity to the contour of the 70 pattern form, the tools rising and lowering to travel as guided by the pilot wheel, until finished as shown in Fig. 4, with the pilot wheel resting on the projecting surface of the 75 pattern form.

It is now plain that with this method of 80 guiding the tools and with the movement of the block synchronized with the movement of the tool that the finished block will be identical in general outline to that of the form.

It is now evident that the length of the 85 machine and the number of centering units and cutting tools have no limit except the limit of economical construction.

By referring to Fig. 2 the dotted lines represent the retired position of the hopper and 90 66 represents a discharge chute into which the turned blocks will drop as they are released from the spur centers.

Obviously the blocks will be severed in two, and finishing will be completed out of the 95 machine.

Having thus described my invention I 95 claim:

1. An automatic block turning machine comprising a frame, a carriage rockably mounted on said frame, a main driving shaft rotatably mounted in said frame, means associated with the main driving shaft to reciprocate said carriage, a tool shaft mounted on said carriage and provided with cutting tools, a pilot wheel carried by said carriage, a plurality of centering mechanisms supported by said frame, spur centers rotatably and slidably mounted in said mechanisms, means to advance or retract said centers simultaneously, means to rotate said centers, pattern form holding centers mounted on said frame and aligned and rotatable with said spur centers, a pattern form mounted in said last named centers and positioned to frictionally engage and rotate said pilot wheel to guide the cutting tools to automatically follow the contour of said pattern form, a feeding chute pivotally and adjustably mounted on said frame and initially positioned with its discharge end interposed between the said spur centers, and means to automatically retire said chute to permit the turning of the block. 110

2. An automatic block turning machine comprising a frame, a laterally positioned carriage rail rotatably mounted in said frame, a carriage rockably mounted on said rail, a main driving shaft rotatably mounted in said frame, means to automatically reciprocate said carriage, a tool shaft mounted on said carriage and provided with cutting tools, means to independently operate said shaft, a pilot wheel idly mounted on said shaft, a 125

- bed formed on said frame, a plurality of centering mechanisms supported by said bed and adapted for laterally spaced adjustment, opposed spur centers rotatably and slidably mounted in said mechanisms, means to automatically advance or retract said centers simultaneously, a clutch controlled driving means associated with the main shaft to rotate said centers, pattern form holding centers mounted on said bed and aligned and rotatable with said spur centers, a pattern form engageable in said form holding centers and positioned to frictionally engage and rotate said pilot wheel to automatically guide the cutting tools to follow the contour of said pattern form, a feeding chute pivotally and adjustably mounted on said bed and initially positioned with its discharge end interposed between the said spur centers, a laterally positioned cam shaft rotatably mounted in said frame and adapted to automatically retire said chute during the turning of the block, and means associated with the main driving shaft to rotate said cam shaft.
3. An automatic block turning machine comprising a frame, a laterally positioned carriage rail rotatably mounted in said frame, a carriage rockably mounted on said rail, a main driving shaft rotatably mounted in said frame, means to automatically reciprocate said carriage, turning tools mounted on said carriage, means to operate said tools independent of the machine, a pilot wheel idly mounted on said carriage, a bed formed on said frame, a plurality of centering mechanisms supported by said bed and adapted for laterally spaced adjustment, opposed spur centers rotatably and slidably mounted in said mechanisms, means to advance or retract said centers automatically with the reciprocating movement of said cutting tools, a clutch controlled driving means associated with the main driving shaft to rotate said centers, a pattern form holding spur center mounted on said bed and aligned and rotatable with the spur centers of the centering mechanisms, and a manually adjustable wood center aligned to rotatably support a pattern form, said pattern form being located to frictionally engage and rotate said pilot wheel to automatically guide the cutting tools to follow the contour of said pattern form, a cam operated feeding chute pivotally and adjustably mounted on said bed and initially positioned with its discharge end interposed between the spur centers of adjacent mechanisms, means operable with the shifting means to control the retiring action of said chute and means to automatically retire said chute during the turning of the block.
5. An automatic block turning machine comprising a frame, a laterally positioned carriage rail rotatably mounted in said frame, a tool carriage reciprocally and rockably mounted on said rail, a main driving shaft rotatably mounted in said frame, means associated with said rail to automatically reciprocate said carriage, a tool shaft mounted on said carriage and provided with cutting tools, means to operate said tool shaft independent of said machine, a pilot wheel idly mounted on said tool shaft, a bed formed on said frame, a plurality of centering mechanisms supported by said bed and adapted for laterally spaced adjustment, opposed spur centers rotatably and slidably mounted in said mechanisms, levers mounted on said centering mechanisms and operable with reciprocating movement of said carriage to provide a shifting means to automatically advance or retract, and start or stop the rotation of said centers with the movement of said shifting means, a form holding spur center mounted on said bed and aligned and rotatable with the spur centers of the centering mechanisms, and a manually adjustable wood center aligned to rotatably support a pattern form, said pattern form being located
4. An automatic block turning machine comprising a frame, a laterally positioned carriage rail rotatably mounted in said

to frictionally engage and rotate said pilot wheel to automatically guide the cutting tools to follow the contour of said pattern form, a cam operated feeding chute pivotally and 5 adjustably mounted on said bed and initially positioned with its discharge end interposed between the spur centers of adjacent mechanisms, clutch operated cams positioned in operable contiguity with the respective chutes 10 and operable with the shifting means to automatically retire and restore said chutes to their initial positions.

6. An automatic block turning machine comprising a frame, a laterally positioned 15 carriage rail rotatably mounted in said frame, a tool carriage reciprocally and rockably mounted on said rail, a main driving shaft rotatably mounted in said frame, an automatic reciprocating mechanism attached 20 to said carriage, a tool shaft mounted on said carriage and provided with cutting tools, adjustably positioned shifting collars mounted on said shaft, means mounted on said carriage to operate said tools independent of 25 said machine, a pilot wheel idly mounted on said tool shaft, a bed formed on said frame, a multiplicity of centering mechanisms supported by and adapted for laterally spaced adjustment on said bed, and provided with 30 opposed spur centers rotatably and slidably mounted therein, a shifting means for said centers comprising levers mounted on the centering mechanisms and operable with the shifting collars to automatically advance or 35 retract said centers, means attached to said levers to stop or start the rotation of said centers with the respective movement of said shifting means, form holding centers adjustably mounted on said bed in aligned 40 and rotatable association with the centering mechanisms, a pattern form carried by said last named centers and adapted to frictionally engage and rotate said pilot wheel to raise and lower the tool shaft to guide the 45 cutting tools in a path identical with the contour of said pattern form, an automatically retractable cam operated feeding chute pivotally and adjustably mounted on said bed and initially positioned with its discharge end interposed between the spur centers of adjacent mechanisms, and means to 50 control the rotation of said cams in synchronized relation to the rotating means of said centers.

55 7. An automatic block turning machine comprising a frame, a laterally positioned carriage rail rotatably mounted in said frame, a tool carriage reciprocally and rockably mounted on said rail, a main driving shaft 60 rotatably mounted in said frame, segments operably attached to said carriage and associated with said rail to automatically reciprocate said carriage, a tool shaft mounted on said carriage and provided with cutting tools, 65 adjustably positioned shifting collars mount-

ed on said shaft, means mounted on said carriage to operate said tools independent of said machine, a pilot wheel idly mounted on said tool shaft, a bed formed on said frame, a multiplicity of centering mechanisms supported by and adapted for laterally spaced adjustment on said bed, and provided with opposed spur centers rotatably and slidably mounted therein, a shifting means for said centers comprising levers mounted on the centering mechanisms and operable with the shifting collars to automatically advance or 70 retract said centers, means to automatically rotate or stop the rotation of said centers with the advancing or retracting movement respectively of said centers, form holding centers adjustably mounted on said bed in aligned and rotatable relation with the centering mechanisms, a pattern form carried by said last named centers and adapted to frictionally engage and rotate said pilot wheel to raise and lower the tool shaft wherewith to guide the cutting tools in a path identical to the contour of said pattern form, an automatically retractable feeding chute pivotally and adjustably mounted on said bed and initially positioned with its discharge end interposed between the spur centers of adjacent mechanisms, clutch controlled cams positioned in operable contiguity with the respective 80 chutes and a bell crank operably mounted on the clutch and operable by means of the shifting levers to automatically control the movement of said chute in synchronized relation to the rotating means of said centers. 85

90 8. An automatic block turning machine comprising a frame, a laterally positioned carriage rail rotatably mounted in said frame, a tool carriage reciprocally and rockably mounted on said rail, a main driving shaft 95 rotatably mounted in said frame, segments operably attached to said carriage and associated with said rail to automatically reciprocate said carriage, a tool shaft mounted on said carriage and provided with cutting tools, adjustably positioned shifting collars mounted on said shaft, means mounted on said carriage to operate said tools independent of said machine, a pilot wheel idly mounted on said tool shaft, a bed formed on said frame, a multiplicity of centering mechanisms supported by and adapted for laterally spaced adjustment on said bed, and provided with opposed spur centers rotatably and 100 slidably mounted therein, a shifting means for said centers comprising levers mounted on the centering mechanisms and operable with the shifting collars to automatically advance or retract said centers, a bell crank attached to said levers and associated with a clutch to stop or start the rotation of said centers with the respective movement of said levers, form holding centers adjustably mounted on said bed in aligned and rotatable relation with the centering mechanisms, a 105
